UNITED STATES PATENT OFFICE.

GEORGE C. BREIDERT, OF CHICAGO, ILLINOIS.

VENTILATOR.

1,358,412.

Specification of Letters Patent. Patented Nov. 9, 1920.

Application filed August 6, 1918. Serial No. 248,515.

To all whom it may concern:

Be it known that I, GEORGE C. BREIDERT, a citizen of the United States, residing at Chicago, in the county of Cook and State of Illinois, have invented certain new and useful Improvements in Ventilators, of which the following is a specification.

My invention relates to a ventilator, and has for its primary object to provide a novel and inexpensive ventilator which will have a maximum capacity for withdrawing impure air from the interior of a building or other structure to which it may be applied without permitting rain or other foreign matter to enter such building through the ventilating passage.

The invention, more specifically, contemplates a ventilator consisting of a hollow structure having a novel arrangement of openings in its side whereby drafts of air will enter one or more of the said openings, irrespective of the direction in which the wind may be blowing, and pass through the ventilator from one side thereof to the other.

A further object is to provide novel arrangements and constructions of corrugated deflecting panels adjacent the openings in the sides of the ventilator, which direct the drafts of air entering the ventilator across the ventilating passages in a manner to accelerate the discharge of impure air, and which are effective in preventing eddy currents of air or back drafts from entering the building through the ventilating passage.

The invention has for further objects such other new and improved arrangements and construction of parts, hereinafter described and claimed, for carrying out the above stated objects and such other incidental objects as will appear from the following description.

The invention is illustrated, in a preferred embodiment, in the accompanying drawings wherein—

Figure 1 is a side view in elevation of a ventilator, constructed in accordance with my invention, applied to the roof of a building.

Fig. 2 is a sectional plan, on an enlarged scale, taken on line 2—2 of Fig. 1;

Fig. 3 is a vertical section through the ventilator, taken on line 3—3 of Fig. 2.

Fig. 4 is a fragmentary view in section,

illustrating the connection between the top and side sheets of the ventilator, the same being made on a larger scale than that shown in Fig. 2.

Fig. 5 is a view similar to Fig. 4 illustrating the connection between the side and bottom sheets of the ventilator.

Fig. 6 is a fragmentary plan section showing the manner in which wire netting is secured across the openings in the sides of the ventilator, and

Fig. 7 is a fragmentary vertical section taken through the top sheet and one of the deflecting panels.

Like characters of reference designate like parts in the several figures of the drawings.

Referring to the drawings, the ventilator is designated generally at 10 and is shown applied to a ventilating stack 11 of the usual form which is secured to the ridge 75 of a gable roof 12. The ventilator consists of a box-like structure or hood made up of a top sheet 13, side sheets 14, and bottom sheet 15. The edges of the top sheet are bent to form U-shaped beads 16 which 80 interlock with hooks 17 formed by bending over the upper edges of the side sheets 14. This form of connection makes a water tight joint between the top and side sheets and prevents any water, drained off the top 85 sheet 13, from entering the interior of the ventilator. The lower edge of the side sheet 14 and the bottom sheet 15 are formed with similar interlocking beads 18 and 19 which prevent water running off the side 90 sheets from entering the interior of the ventilator. The side sheets are spaced apart so as to provide openings 20 at the vertical corners of the hood 10 to permit drafts of air to pass through the interior of the hood 95 irrespective of the direction in which the wind may be blowing. These openings are preferably covered with strips of wire netting 21 secured in beads 22, 22 formed on the adjacent vertical edges of the side sheets 100 14. The wire netting is preferably of a large mesh and stands within the vertical edges of the side sheets 14 so as not to interfere with air passing through or across the spaces 20 intervening between the edges 105 of these sheets. The bottom sheet 14 has a central orifice 23 which is preferably annular in shape, the edge thereof being turned downwardly to provide an attaching flange 24. The disk removed by cutting the ori-

5 fice 23 is preferably formed into a cone 25 and secured to the center of the top sheet 13 so as to prevent the accumulation of water on the top of the ventilator. A tubular neck 26, providing a ventilating passage 27, extends through the orifice 23 of the bottom sheet and provides an upstanding flange 28 surrounding said orifice. The flange 24 rests upon an enlargement 29 of 10 the neck and is slightly larger in diameter than the neck so as to permit any rain, blown into the ventilator through the openings 20, to pass out at the joint between the flange 24 and the outer surface of the 15 neck. The hood may be riveted or otherwise secured to the neck so as to make the structure rigid, though this connection should not provide a water tight joint. It will be obvious that the upper end of the 20 ventilating stack 11 could be used as the neck portion of the ventilator if desired.

25 Drafts of air entering the ventilator through the openings 20 are directed through the ventilator toward another opening 20 by means of air deflecting panels 30 which are arranged opposite the openings 20. These panels are substantially V-shaped in cross-section and are spaced apart to provide discharge openings 31 which communicate with the ventilating passage 27 in the 30 neck. These panels are also preferably formed with transverse corrugations 32 which provide horizontal channels which direct the air impinging against the panels 35 in a horizontal course across the discharge openings 31 and prevent swirling or eddy currents within the ventilator.

40 Referring to Fig. 2 of the drawings, it will be noted that drafts of air blowing in the direction indicated by the unfeathered arrows will enter the openings designated A—B and pass across the discharge openings designated C—D and exhaust through 45 openings E—F. Drafts of air blowing in the direction indicated by the feathered arrows will enter the ventilator through the opening A, pass across the discharge openings D—G, and exhaust through the openings E—B. The drafts of air passing across 50 the discharge openings 31 in this manner create a suction which causes the air from the interior of the building to be drawn out through the passage 27.

55 While I have shown and described my invention in one specific embodiment, it will be obvious that modifications can be made without departure from the spirit of my invention. I, therefore, do not wish to limit my invention to the exact structure disclosed except so far as specific limitations 60 may appear in the appended claims.

I claim:

65 1. A ventilator comprising a hollow structure having openings for the admission of drafts of air, and baffles providing ventilat-

ing passages and formed with transverse corrugations adapted to direct the incoming drafts of air across said passages.

2. A ventilator comprising a box-like structure having openings at the corners 70 thereof adapted to admit drafts of air, and corrugated panels arranged adjacent said openings to direct the incoming drafts of air through said structure.

3. A ventilator comprising a box-like 75 structure having openings at the corners thereof adapted to admit drafts of air, and panels arranged adjacent said openings and formed with transverse channels which provide air impinging surfaces adapted to direct the incoming air toward another of said 80 openings.

4. A ventilator comprising a box-like structure having openings to admit drafts of air to the interior thereof, and panels 85 arranged adjacent said openings and formed with transverse ribs which direct the incoming air through said structure.

5. A ventilator comprising a box-like structure having openings in its sides to admit 90 drafts of air, and panels formed with transverse corrugations and arranged adjacent said openings; said panels being spaced apart to provide ventilating orifices and adapted to direct the incoming drafts of 95 air across said orifices.

6. A ventilator comprising a box-like structure having openings in its sides to admit drafts of air, and angular panels formed with transverse corrugations and arranged 10 adjacent said openings; said panels being spaced apart to provide ventilating orifices and adapted to direct the incoming drafts of air across said orifices.

7. A ventilator comprising a box-like 10 structure having openings in its sides to admit drafts of air, and substantially V-shaped panels arranged adjacent said openings and formed with transverse corrugations which direct the incoming drafts of air through 11 the said structure.

8. A ventilator comprising a box-like structure having openings to admit drafts of air to the interior thereof, and substantially V-shaped panels formed with transverse corrugations and arranged adjacent 11 said openings; said panels being spaced apart to provide ventilating orifices and adapted to direct the incoming drafts of air across said orifices.

9. A ventilator comprising a box-like structure, the side plates of which are spaced apart to provide openings to admit drafts of air, and corrugated deflecting panels arranged opposite said openings to direct the incoming drafts of air through 12 said structure.

10. A ventilator comprising a box-like structure, the side plates of which are spaced apart to provide openings at the corners of 130

5 said structure adapted to admit drafts of air, wire netting fitted across said openings within the edges, and corrugated deflecting panels arranged opposite said openings to direct the incoming drafts of air through said structure.

10 11. A ventilator comprising a box-like structure having openings to admit drafts of air and with a discharge orifice in the bottom, a tubular member extending through said orifice and providing an upstanding flange, and air deflecting panels arranged in front of said openings to direct the incoming drafts of air horizontally across said structure; said deflecting panels being provided with air collecting surfaces to prevent the formation of swirling or cross currents of air within the ventilator.

15 12. A ventilator comprising a box-like structure having openings to admit drafts of air and with a discharge orifice in the bottom, a tubular member extending through said orifice and providing an upstanding flange, and air deflecting panels formed with transverse corrugations and ar-

20 ranged in front of said openings to direct the incoming drafts of air horizontally across said structure.

25 13. A ventilator comprising a top sheet having its edges bent inwardly to form U-shaped beads, a bottom sheet having its outer edges bent under the sheet to provide beads and having a central opening, side sheets having bent portions at their upper and lower edges adapted to interlock with the beads formed on the top and bottom sheets, respectively, and are spaced apart to provide openings adapted to admit drafts of air, transversely corrugated deflecting panels arranged opposite said openings, and a tube 30 extending through the central opening in the bottom sheet to provide an upstanding baffle and adapted to fit over the draft stack of a building; said bottom sheet being formed with a flange which is secured to 35 the tube, a slight distance between the tube and flange being provided to permit water to drain out of the ventilator.

GEORGE C. BREIDERT.
